4 Claims

ABSTRACT OF THE DISCLOSURE

A fountain type wand defining a handle at one end and having a panel-like head at its other end of greater length than width and disposed transverse to the longitudinal axis of the wand. The head is mounted on the wand for oscillation about an axis extending transversely of the wand and generally paralleling the longitudinal center line of the head. An endwise outwardly opening U-shaped frame is supported from the end of the wand remote from the handle and the head is oscillatably supported between the free ends of the legs of the U-shaped frame. A soft cover is provided for the head and is constructed of a material through which fluids may pass and which is capable of retaining a given quantity of fluids in the manner of a sponge. The cover not only covers the head but also one side of the supporting frame and the head is in the form of a manifold to which cleaning fluids under pressure may be supplied and includes outlet openings opening outwardly of the side of the frame which is covered by the soft cover. Further, the cover is provided with an opening in registry with the outlet openings in the head whereby water and other cleaning fluids may be discharged from the manifold in jet fashion without passing through the material of the cover.

The car washing assembly of the instant invention has been specifically designed to provide a means whereby a car or other vehicles as well as various stationary objects may be cleaned with a minimum of effort. The assembly includes a wand defining a handle at one end and having a head oscillatably supported from its other end from which cleaning fluids may be discharged in jet fashion and which is covered by means of a soft cover having water absorbent properties.

By supporting the head of the assembly from the wand for oscillation relative to the latter the head, which is generally panel-like in configuration, may more readily conform to irregular surfaces over which the head is passed by a person holding the handle end of the wand.

The head end of the wand includes means for attaching the outlet end of a fluid supply line to the wand and ducting fluids from the supply line to the interior of the manifold-type head which is provided with outlet openings for jet discharging fluids therefrom.

The handle end of the wand includes valve means whereby the flow of fluids under pressure to the manifold-type head may be adjustably controlled and the cover for the head is secured thereover in removable fashion whereby it may be removed for cleaning and/or replacement whenever desired.

The main object of this invention is to provide a car washing assembly of the fountain wand type which may be readily used in washing automobiles as well as other vehicles and stationary objects.

Another object of this invention, in accordance with the immediately preceding object, is to provide a car washing apparatus having a scrubbing head on one end of the wand portion thereof supported from the head for oscillation about an axis extending transversely of the wand to thereby enable the head to more readily conform to irregular surfaces over which the wand is passed.

2

Yet another object of this invention is to provide a car washing assembly in accordance with the preceding objects and provided with a removable and replaceable soft water absorbent cover enclosing the head thereof whereby various vehicle surfaces over which the head is moved will be protected against scratches and will be lightly scrubbed by the car washing apparatus.

Still another object of this invention is to provide a car washing assembly including a removable oscillatory head.

A final object of this invention to be specifically enumerated herein is to provide a car washing assembly which will conform to conventional forms of manufacture, be of simple construction and easy to use so as to provide a device that will be economically feasible, long lasting and relatively trouble free in operation.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a fragmentary perspective view of the car washing assembly;

FIG. 2 is an enlarged fragmentary plan view of the head end of the car washing assembly;

FIG. 3 is a fragmentary vertical sectional view taken substantially upon the plane indicated by the section line 3—3 of FIG. 2; and

FIG. 4 is a fragmentary perspective view of the head end of the car washing assembly with the cover therefor in an exploded position.

Referring now more specifically to the drawings the numeral 10 generally designates the car washing assembly of the instant invention which comprises a modification of the pressurized paint supply assembly with extension applicator disclosed in my prior U.S. Pat. No. 3,376,096.

The assembly 10 includes an elongated handle or wand 12 having a handle end 14 and a head end 16.

Secured to the head end 16 as an integral portion thereof is an inlet fitting 18 for fluids and the fitting 18 includes an inlet port 20 and an outlet port 22. The inlet end of an extension tube 24 is secured in the outlet port

22 at one end and includes an outlet fitting 26 on its opposite end. The extension tube 24 projects endwise outwardly of the end of the fitting 18 remote from the handle end 14 and is secured along its length to one side of a triangular mounting plate 28 secured at one of its apices to the inlet fitting 18. The base edge of the mounting plate 28 remote from the apex thereof secured to the fitting 18 is secured along its length to the midportion of the bight portion 30 of a support frame referred to in general by the reference numeral 32. The support frame

32 includes a pair of generally parallel legs 34 which project endwise outwardly from the opposite ends away from the bight portion 30 and in a direction away from the handle end 14 of the wand 12. The outer free ends of the legs 34 include inwardly directed terminal end

portions 36 which comprise stub axle members by which a generally panel-like elongated head 38 is oscillatably supported between the free ends of the legs 34. The head 38 includes a center longitudinally extending manifold outlet pipe 40 provided with longitudinally spaced liquid jet outlet openings 42 and a pair of longitudinally extending resiliene elongated bumper members 44 spaced on opposite sides of the manifold outlet pipe 40.

The manifold pipe 40 and bumper members 44 project outwardly from one side of the head 38 and the legs 34 are covered by resilient tubing members 46.

The head 38 includes a transverse supply pipe 48 which

extends transversely thereof centrally intermediate its opposite ends and the outlet end of the supply pipe opens into the center of the outlet pipe 40. The inlet end of the supply pipe includes an inlet fitting 50 and the outlet fitting 26 of the extension tube 24 is communicated with the inlet fitting 50 of the supply pipe 48 by means of a length of flexible tubing 52 extending and connected between the fittings 26 and 50.

The intersections of the opposite ends of the bight portion 38 with the base ends of the legs 34 are reinforced by mean of triangular gusset plates 54 and the handle or wand 12 is provided with a longitudinally extending header pipe 56 supported therefrom by means of clamp assemblies 58 and having its outlet end provided with a fitting 60 coupled to the fitting 20 for connecting the discharge end of the header pipe 56 to the fitting 18. The inlet end portion of the header pipe 56 includes a manually actuatable lever-type valve assembly referred to in general by the reference numeral 62 and the valve assembly 62 includes a discharge fitting 64 coupled to the inlet end of the header pipe 56 and an inlet fitting 66 to which the outlet end of a flexible liquid supply hose 68 is connected. Of course, the length of the wand 12 and its companion header pipe 56 may be as desired and any type of liquids under pressure may be supplied to the assembly 10 through the supply hose 68 for discharging from the outlet manifold pipe 40.

A removable cover is illustrated in FIGS. 1 through 4 and referred to in general by the reference numeral 70. The cover 70 is in the shape of a rectangular envelope including front and rear side walls 72 and 74 joined along their corresponding upper and end marginal edge portions. The side wall 72 includes a lower extension 76 which overlies the side face of the frame 32 outwardly from which the outlet openings 42 open and the lower edge portion of the rear side wall 74 and the lower edge portion of the extension 76 include coacting tie straps 78 which may be tied together in the manner illustrated in FIGS. 2 and 3 of the drawings. In addition, the opposite side edge portions of the extension 76 include coacting tie straps 80 which may also be secured together in the manner illustrated in FIG. 2 of the drawings in removably securing the cover 70 over the head 38 and side of the frame 32 to which the outlet openings 42 open.

The cover 70 is constructed of any suitable soft and flexible material having water absorbent properties and is provided with a soft nap 82 on its outer surfaces. Further, the front side wall 72 of the cover 70 includes an opening 77 having a strap 77' secured across its central portion and the opening 77 is registered with the manifold outlet pipe 40 whereby liquids delivered under pressure to the manifold outlet pipe 40 may be discharged in jet fashion from the outlet openings 42 without passing through any wall portion of the cover 70.

It will be noted that the resilient bumper members 44 are covered by those portions of the front wall 72 disposed immediately above and below the opening 74 and therefore that the bumper members 44 back the front wall or panel 72 in order that greater pressures may be applied to the surface being cleaned over which the head 38 and cover 70 are being passed. In this manner, the surfaces being cleaned may be lightly scrubbed by the soft cover 38 without marring the surface.

The cover 70 is made so that it may be readily removed whenever desired for cleaning or replacement and the free ends of the legs 36 may be spread apart in order

to remove the head 38 after the connection between the inlet fitting 50 and the flexible pipe or hose 52 has been released.

Of course, any suitable cleaning liquids may be supplied to the assembly 10 and such cleaning fluids may be in the form of soapy water or clean water for cleaning vehicle bodies.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention.

What is claimed as new is as follows:

1. An apparatus for washing vehicles and the like, said apparatus comprising an elongated handle including a first handle end and a second head end, an elongated generally panel-like head supported endwise outwardly of said head end of said handle with said head disposed transverse to said handle and supported therefrom for oscillation about an axis extending longitudinally of said head, said head including elongated liquid manifold means extending therealong including longitudinally spaced liquid jet outlet means opening outwardly of one side face of said head, a soft liquid absorbent cover removably secured over said head, and means operative to communicate the interior of said liquid manifold means with a source of liquid under pressure, said cover including an elongated opening therein with which said liquid jet outlet means are registered and through which jets of liquid supplied to said manifold means under pressure may be discharged in jet fashion without having to pass through any wall portion of said cover.

2. The combination of claim 1 wherein the last mentioned means includes a header pipe supported from and extending along said handle with means adjacent the handle end of the handle for coupling a liquid supply hose to said header pipe and means, including a flexible tube section, coupling said header pipe to said manifold means.

3. The combination of claim 1 wherein said one side face of said head includes a pair of generally parallel outwardly projecting rib-like resilient members generally paralleling said axis and disposed on opposite sides of said liquid jet outlet means, the portions of said cover disposed on opposite sides of said opening overlying said resilient members so as to be backed by the latter.

4. The combination of claim 1 including a generally U-shaped frame carried by the head end of said handle and opening endwise outwardly of the latter, said head being oscillatably supported between the free ends of the legs of said frame.
